Primary Examiner — Marianne Pandozzi

Assistant Examiner — Jae Liang

(57) **CLAIM**

The ornamental design for a handle with hook, as shown and described.

DESCRIPTION

FIG. 1 is a perspective view of a handle with hook in use with a bottle showing my new design;

FIG. 2 is a front elevational view thereof;

FIG. 3 is a rear elevational view thereof;

FIG. 4 is a right side elevational view thereof; the left side elevational view being a mirror image thereof;

FIG. 5 is a top plan view thereof; and,

FIG. 6 is a bottom plan view thereof.

The broken lines in the drawing depict environmental subject matter only and form no part of the claimed design.
